Des. 230,291

Patented Feb. 5, 1974

230,291

MARBLE RUNWAY

Thomas Josef Derrick Paul Karen, Ashwell, England, assignor to Hilary Page "Sensible" Toys Limited, Kenley, Surrey, England

Filed Apr. 27, 1972, Ser. No. 248,343

Term of patent 14 years

Int. Cl. D21—01

U.S. Cl. D34—15 K

FIG. 1.

FIG. 2.

FIG. 3.

FIG. 4.

FIG. 5.

FIG. 1 is a perspective view of a marble runway showing my new design;

FIG. 2 is a side elevational view;

FIG. 3 is a bottom plan view;

FIG. 4 is a top plan view; and

FIG. 5 is a sectional view taken on the line 5—5 of FIG. 1.

I claim:

The ornamental design for a marble runway, as shown.
